GRINDER FOR SHARPENING CUTLERY

Filed Dec. 31, 1948

FIG. I.

FIG 2

FIG. 4

FIG. 3.

INVENTOR;
FRED W. KUBLIN,

BY *Lawrence F. Cohn*
ATTORNEY

UNITED STATES PATENT OFFICE

2,570,564

GRINDER FOR SHARPENING CUTLERY

Fred William Kublin, St. Louis, Mo., assignor to
Dazey Corporation, St. Louis, Mo., a corpora-
tion of Delaware

Application December 31, 1948, Serial No. 68,530

3 Claims. (Cl. 51—111)

1

My invention relates to improvements in grinders for sharpening cutlery, and particularly to an improved tool of this character which is especially suitable for household use.

The principal object of my invention is to provide a small, compact, highly efficient sharpening machine.

An important object of the invention is achieved in the provision of an improved two-stage velocity increasing gear mechanism wherein a manual crank and a grinding wheel driven thereby are mounted in coaxial relation on opposite sides of a bracket arm that forms a housing for the gear mechanism.

Another object resides in the provision of improved means for supporting a tool for sharpening purposes at one side of the grinding wheel.

These and other objects and advantages will appear from the following description of a practical and presently preferred embodiment of my invention, reference being made to the accompanying drawing wherein:

Fig. 1 is a side view with a portion of the side wall of the housing and the crank member broken away;

Fig. 2 is a plan sectional view partly in section, as taken at section line 2—2 of Fig. 1;

Fig. 3 is a fragmentary sectional view as taken at line 3—3 of Fig. 2, and

Fig. 4 is an inner end view of the grinder.

Referring now to the drawing, the body or frame structure of the grinder is a hollow arm-like housing designated generally 1, consisting of a pair of complementary sheet metal sections 2 and 3. These sections fit together at their margins, the section 2 having a peripheral bead 4 which accommodates and conceals the margin of section 3. The sections are secured together by pins 5 which are driven into the ends of a tubular spacer that provides a bearing for a gear assembly to be hereinafter designated and described. The housing sections are also secured together at one end by a plate 7 having openings through which extend lugs or tabs 8 and 9 formed integrally on the ends of the housing sections. These tabs are projected through openings in the end plate 7 and are bent over as shown in Fig. 4. The plate 7 constitutes a wall mounting element and has downwardly convergent side edges for detachable connection with a correspondingly shaped socket plate (not shown), which is adapted to be secured to a wall or other support.

There is formed in the housing section 2 near the end thereof remote from the wall mounting plate a circular opening and the marginal metal

2

surrounding this opening is turned inwardly to form an annular rim or collar 10. The rim 10 serves to position a cup-shaped member 11 having a base flange 12 by which it is welded or otherwise suitably secured to the housing section 2. The member 11 constitutes a bracket or support for a shaft 13 which extends centrally through the cup-shaped bracket 11 and is rigidly secured thereto. Securement of the shaft to the bracket is effected by means of a flanged collar 14 which is press-fitted on the shaft and is welded to the end wall of the cupped bracket 11.

The shaft 13 projects centrally through an opening 15 formed in the side wall of the housing section 3, and with the flanged collar 14 provides a bearing for a gear and crank assembly. This assembly includes a relatively large gear 16 and a crank 17 having a flanged hub part 18 which is permanently secured to the gear 16 as by welding. A recessed portion 19 of the crank 17 is provided with an opening to receive the shaft 13 and the described assembly is retained on the shaft by a spring retainer ring 20. A rotatable manipulating knob 21 is provided on the free end of the crank.

The gear 16 meshes with and drives a small pinion gear 22 fixed to a sleeve 23 which is journaled for rotation on a stationary bearing sleeve 24, the latter being secured at its ends to the housing sections 2 and 3 by the headed pin 5, previously referred to. A relatively large gear 25 is also fixedly secured to the sleeve 23 and this gear projects through an opening 26 formed in one side wall portion of the cupped shaft bracket 11. The gear 23 meshes with and serves to drive a small pinion gear 27 keyed to the inner end of a bearing sleeve 28 which is journaled on the stationary shaft 13. The sleeve 28 is of hexagonal external section, and a grinding wheel 29 having a hexagonal central opening is mounted on the sleeve and adapted to be turned thereby.

The grinding wheel 29 is preferably composed of a pair of half sections 29a and 29b having bevelled inner peripheral edges which together form a V-shaped groove 39. The wheel sections are normally held in pressure engagement with each other by a spring 30. A washer 31 retains the wheel sections on the sleeve 28.

The stationary shaft 13 projects outwardly beyond the end of the grinding wheel bearing sleeve 28 to provide a mounting for a tool rest 32. This tool rest comprises a sleeve having a flange from which projects a plate 33 disposed at an angle to the side surface of the wheel. The plate 33 is adapted to support an edged tool such

as a scissors blade and hold the same at the proper angle to the side of the wheel. The tool rest 32 is adapted for angular adjustment about the shaft 13 and is retained on the shaft by a retainer ring 34 which seats in grooves formed in the said shaft and in the sleeve of the tool rest.

I have described my invention with reference to a preferred, practical working embodiment thereof. It will be understood that changes may be made without departing from the spirit and full intendment of the invention which is defined in the appended claims.

I claim:

1. A cutlery grinder comprising an elongated housing having mounting means at one end, a bracket disposed within and fixed to said housing near its opposite end, a stationary shaft rigidly secured at an intermediate point to said bracket, said shaft projecting laterally from said housing, a grinding wheel at one side of said housing, rotatably mounted on said shaft, a driven gear disposed within the housing and fixed to said grinding wheel, said shaft projecting outwardly beyond the outer side face of said wheel, a tool rest mounted on said projecting outer end of said shaft, a crank disposed at the opposite side of said housing, and rotatively mounted on said stationary shaft, a driving gear fixed to said crank and disposed within the housing, a rotatable countershaft in said housing spaced between said stationary shaft and said housing mounting means, and a pair of gears fixed to said countershaft and operatively engaging said driving and driven gears.

2. A cutlery grinder comprising an elongated housing, means at one end for attaching the housing to a support, said housing having an internal bracket member near its opposite end, a stationary shaft rigidly secured at an intermediate point to said internal bracket member, said shaft projecting laterally from the housing, a grinding wheel at one side of said housing, rotatably mounted on said stationary shaft, a driven gear rotatable on said shaft and fixed to said wheel, a manual crank at the opposite side

of said housing rotatably mounted on said stationary shaft, a driving gear fixed to said crank and disposed within the housing, a rotatable countershaft in said housing spaced between said stationary shaft and said end mounting means, and a pair of gears fixed to said countershaft in meshing engagement with said driving and driven gears.

3. A cutlery grinder comprising a hollow elongated casing having means at one end for attaching the casing to a support, a cup-shaped bracket secured to a side wall within the casing, a stationary shaft secured intermediate its ends to said bracket, said shaft extending transversely through and projecting from opposite sides of the casing, a crank at one side of the casing rotatable on said shaft, a sleeve rotatable on said shaft and projecting from the opposite side of the casing, a grinding wheel mounted on said sleeve for rotation therewith, gear means in the casing operatively interconnecting said sleeve for rotation by said crank, and a tool rest comprising a collar disposed for rotational adjustment on the outer end of said shaft and a tool supporting plate secured to said collar.
